UNITED STATES PATENT OFFICE.

LOUIS VOLAT, OF BUFFALO, NEW YORK.

DESIGN FOR A CHILD'S CAP.

No. 40,028.

Specification for Design.

Patented June 1, 1909.

Application filed April 5, 1909. Serial No. 488,134. Term of patent 7 years.

To all whom it may concern:

Be it known that I, LOUIS VOLAT, a subject of the Emperor of Russia, residing at Buffalo, in the county of Erie and State of New York, have invented a new, original, and ornamental Design for Children's Caps, of which the following is a specification, reference being had to the accompanying drawing, forming part thereof.

looking at the same from the front and underside. Fig. 2 is a similar view looking at the cap from the rear and top thereof.

I claim:

The ornamental design for a child's cap, as shown.

LOUIS VOLAT.
